UNITED STATES PATENT OFFICE.

EDMUND KOLBEN, OF NEW YORK, N. Y.

IMPROVEMENT IN NAIL-BUTTONS.

Specification forming part of Letters Patent No. 122,468, dated January 2, 1872.

Specification describing an Improvement in Button-Nails or Nail-Buttons, invented by EDMUND KOLBEN, of New York city.

The article is a nail having a head like the body of a richly-covered button. It may be driven with a hammer having a face of soft material, for which I propose to make another application for patent. The importance of the soft face of the hammer is to avoid injury to the rubber or other soft material covering the head.

I proceed to describe what I consider the best means of carrying out my invention.

The accompanying drawing forms a part of this specification.

Figure 1 is a longitudinal section, and Fig. 2 is a plan view with the top of the button-head removed. This figure shows the nail with the under lining B and collet C applied together without the additional parts.

Similar letters of reference denote like parts in both the figures.

I take well-made tacks—say twelve or fourteen ounces to the thousand—formed with large strong heads and smooth round shanks. These form the bodies and points of my improved nail, and also the central or innermost portion of the head. I have marked this part A A', the latter distinguishing the ordinary large tack-head. I provide all the materials, except the eyes, as if about to manufacture ordinary rich-covered buttons. I thrust the point and body of the tack through a piece of paste-board, or the like, as shown by B, and through a collet, C, and apply it, with its attachments, within a cap, E, of metal, with a lining piece, D, and a covering piece, G, exactly as if to manufacture covered buttons, and using a press suitably prepared to accommodate the long nail instead of

an ordinary eye, press the parts forcibly and properly together, the same as in completing an ordinary covered button. The button-head is strongly and stiffly secured, and presents the same rich and attractive appearance as buttons with eyes, while the nail may be driven with or without pricking a hole therefor previously, and will attach the button stiffly and strongly to any material into which it may be driven. It may be used merely for ornament, or both for ornamentation of the work and for holding cloth, leather, or the like.

I can use all the varieties of sizes of heads and all the varieties of materials and proportions of thickness of the head, and of convexity or concavity which are used in ordinary buttons. I can use any length of nail which may be desired. I consider it important that the nail shall have a large head; but it is not important that the head be smooth or in any degree ornamental. On the contrary the completeness with which it is covered renders these points absolutely non-essential. I propose to tin the nail in some cases, or to manufacture the nail of brass to avoid trouble from rusting.

I claim as my invention—

The within-described button-nail, having the head A' stiffly held between a metallic collet, C, and a metallic cap, E, with suitable lining material and with a covering piece, G, of woven or analogous soft fabric covering the cap, the whole forming a nail with a head covered with fabric, as specified.

In testimony whereof I have hereunto set my name in presence of two subscribing witnesses.

EDMUND KOLBEN.

Witnesses:

C. C. LIVINGS,
ARNOLD HOERMANN.
